INTERCHANGEABLE PENCIL

Georg Keller, Nuremberg, Germany

Application April 22, 1938, Serial No. 203,645
In Germany May 10, 1937

6 Claims. (CL 120—14)

The present invention relates to magazine pencils in which a plurality of lead holders are arranged to be selectively moved into a position for use of the lead carried by one holder.

5 Interchangeable pencils for various coloured leads having a plurality of lead holders are known in which the individual lead holders are selectively brought into the thrust forward position by means of a thrust handle and may also 10 in some cases be withdrawn again by hand. Return springs are also known, and either one return spring is provided for each individual lead holder or a common return spring is provided for all the lead holders. The lead holders in 15 this case are held in the advanced position by a locking device and are automatically withdrawn after the locking device is released. Each lead holder moreover takes part in the rotary drive for the advance of the lead, this rotary drive being first applied to a resilient arm which is provided with a thrust handle that projects through a slot in the pencil casing. For this reason a separate slot in the pencil casing is necessary for 20 each individual lead holder. An equal number of openings of considerably greater width than that 25 of the slots in the pencil casing are provided as supports for the locking device. Owing to these various openings in the casing of the pencil, and there may be for example eight of them, not only 30 is the entire outward appearance of the pencil impaired, but the casing of the pencil is also weakened to such an extent that it is only possible to make it of metal.

Moreover these many openings promote the 35 entry of dirt, particles of material from the pocket and the like into the interior of the pencil, whereby in certain circumstances the operation of the component parts thereof may be prejudiced.

In order that the openings in the casing of the 40 pencil should not have to be made still larger, the parts, which serve for displacing the lead holders and which project out of the casing of the pencil, consist for the most part of relatively small knobs. Considerable difficulties are consequently 45 experienced by men with large hands and fingers roughened by manual labour in rapidly and surely effecting the displacement.

The assembly of the many component parts of 50 such a multi-colour interchangeable pencil presents further difficulties. These disadvantages are removed by the present invention in that, in spite of good and effective locking of the lead holders in the advanced position, extra large 55 openings in the pencil casing such as were pre-

viously necessary for the locking of the lead holders are no longer necessary and in that, in one particular constructional form, there is provided, instead of a plurality of slots for the thrust handles, only a single slot for the thrust movement. 5

According to the present invention there are therefore provided, in the casing of an interchangeable pencil having a plurality of lead holders supported in the thrust forward position, only the slots which are necessary for the thrusting 10 forward of the lead holders by means of the thrust handles and the supporting members, which are so arranged that they are completely covered in the interior of the casing of the pencil and that parts of the lead holders rest in the 15 thrust forward position against the supporting members, the disengagement of the supporting members being effected only by the pressure of the thrust handle.

The invention is illustrated by way of example 20 in the accompanying drawing in which:

Fig. 1 is an elevation of an interchangeable pencil,

Fig. 2 is an elevation of an interchangeable pencil in another constructional form,

Fig. 3 is an elevation of the interchangeable pencil shown in Fig. 2, the pencil having been rotated through 180°,

Fig. 4 is a longitudinal section through the pencil illustrated in Fig. 3 with parts broken 30 away.

Figs. 5, 6, 8 and 9 are elevations of component parts,

Fig. 7 is a section on the line VII—VII of Fig. 6,

Figs. 4 to 9 are on an enlarged scale about twice 35 the actual size.

In the drawing, 1 indicates the pencil casing, 2 the lead holders, 3 the leads, 4 the thrust handles, and 5 the slots in which the thrust handles move for the thrust and withdrawal movements.

According to the invention the only slots provided are the slots 5 for the thrust movement (see Fig. 1), one such slot 5 being provided for each lead holder.

The invention will however be illustrated in greater detail with reference to a particularly 45 advantageous constructional embodiment in which only a single slot 5 is provided (see Figs. 2 to 4).

In the embodiment shown in Figs. 2 to 4, a 50 sleeve 6 is inserted and can be secured in any desired manner in the casing 1 of the pencil. Such mounting of the sleeve 6 is effected by means of a pocket clip 7, the part 8 of which is connected, for example a screw 9, with other parts of the 55

pencil. For this purpose a plate 10 which is larger than the part 8 is attached to the latter. This plate 10 engages in a recess 11 in the sleeve 6 which is also provided with a longitudinal slot 12 which enables the sleeve to be inserted in the interior of the pencil casing after the parts 7, 8 and 10 have previously been introduced from the inside towards the outside of the same.

It is essential that supporting members for the 10 lead holders should be arranged completely covered within the pencil casing. In the constructional example illustrated, a slotted tube 13 is secured in the interior of the sleeve 6, for example by means of the screw 9. The lead holders 2 are 15 provided with a resilient part, for example a leaf spring 14, on the end portion 15 of which is secured the thrust handle 4. The arrangement is such that, as each lead holder is thrust forward, the end edge 16 of the leaf spring 14 rests against 20 the edge 17 of the slotted tube 13 and is consequently locked in this position. For this purpose the leaf springs are provided with outward tension, for example they are bent outwardly at 18. The leaf springs 14 are guided, during the movement of the lead holders 2, by a guide member 20 which advantageously serves as a lead receptacle 19. The guide member may be hollow as shown in Fig. 7 and provided with longitudinally extending ribs 21. This guide member is secured 25 in an annular member 22 having a screw-threaded part 23 adapted to be connected with a rotatable knob 24. The annular member 22 is provided with four slots 31. This consequently permits the lead holders to rotate in the casing of 30 the pencil and hence enables the adjustment of the selected thrust handle 4 relative to the single slot 5 to be effected.

The slotted tube 13 at the end 25 is provided with inclined cam surfaces 26 so that the guide member 20 is drawn outwards with the lead holders somewhat in the direction of the arrow A when the knob 24 is rotated, until one of the thrust handles 4 moves into a recess 28 in the end 25 and the thrust handle of the lead holder to be selected is adjusted relatively to the slot 5. The guide member 20 and the annular member 22 are yieldably urged in a direction opposite to the arrow A by means of a spring 27 arranged between the lower end of the sleeve 6 and a washer 32. The washer is prevented from moving downwardly on the guide member 20 by means of pin 33. The thrust handle aligned with the slot 5 is then simply thrust forward until the part 15 of the leaf spring 14 comes to rest with its edge 16 against the edge 17 of the slotted tube 13, whereby the lead holder is locked in the writing position and cannot slide back even when considerable pressure is applied to the point of the lead during writing.

For the purpose of disengagement from the supporting member it is only necessary to press the thrust handle inwards, whereupon its lead holder can be drawn back into the interior of the pencil casing.

The colours of the individual leads may be indicated in known manner either on the thrust handle 4 or on a covering sleeve 29 behind the thrust handle 4.

The position of the parts shown in Fig. 4 illustrates one of the holders 2 in an operative position for writing with the lead 3 carried thereby. The lead holder protruding from the casing may be withdrawn by moving the handle 4 upwardly to disengage the end 16 of the spring 14 from the shoulder 17 provided by the slotted tube 13.

During this upward movement the handle 4 passes in the slot 5 of the casing 1. The spring 14 moves in the groove 5a of the guide member 20 and the upper end of the spring is prevented from moving radially outward since the slot 5 is narrow enough to provide guiding means for the spring 14. The handle 4 may thus be retracted into one of the openings 31 provided in the annular member 22.

Another lead may be moved into a writing position at the point of the pencil casing by rotating the knob 24 until the lead of the desired color is aligned with the slot 5. This alignment is provided when another of the handles 4 moves into the recess 28. Thus the handle 4 aligned with the slot 5 can be moved downwardly to project the corresponding lead holder beyond the pointed end of the casing. The end 16 of the spring 14 will thus engage the shouldered edge 17 of the slotted tube 13 and prevent the lead holder from 20 moving upwardly in the pencil while writing.

Having now particularly described and ascertained the nature of my said invention, and in what manner the same is to be performed, I declare that what I claim is:

1. In a pencil, a casing, a plurality of lead holders longitudinally movable in the casing, a yieldable member attached to each lead holder and having a thrust handle, said casing having a longitudinally extending slot, rotatable means 30 supporting said yieldable members so that each handle may be supported in a position to be moved into said slot, a slotted tube fixed within the casing providing a transverse shoulder, a sleeve arranged within the casing embracing said 35 yieldable members adjacent said shoulder whereby the transverse shoulder is engaged by a yieldable member when the same is moved to a forward position in the casing.

2. In a pencil, a casing having a longitudinal 40 slot therein, a plurality of lead holders longitudinally movable in the casing, rotatable means for guiding said lead holders during longitudinal movement thereof, each of said lead holders having an actuating handle adapted to be moved in 45 said slot, a slotted tube fixed within the casing providing a transverse shoulder at the forward end thereof and a recess in the rear end, a spring urging said guide means towards the forward end of the casing, said rotatable guide means supporting said handles and in operable relation with respect to said recess, and said recess being so positioned with respect to said slot that one of the handles will be aligned with said slot when another of the handles moves into said recess.

3. In a pencil, a casing, a plurality of lead holders longitudinally movable in the casing, a yieldable member attached to each lead holder and having a thrust handle, said casing having a longitudinally extending slot, rotatable means 60 supporting said yieldable members so that each handle may be turned to a position to be moved into said slot, a sleeve fixed within the casing, a slotted tube fixed within the sleeve embracing said yieldable members whereby the edge of said 65 tube is engaged by a yieldable member when the same is moved to a forward position in the casing.

4. In a pencil, a casing, rotatable means having a guide member provided with grooves, a lead holder having a leaf spring adapted to be 70 longitudinally moved in said groove, said casing having a slot therein longitudinally aligned with a slot in a sleeve fixed in the casing, a slotted tube fixed within the sleeve, a handle carried by said leaf spring adapted to project through 75

said slots, and said leaf spring being deformed adjacent the handle so as to engage the edge of said tube when the lead holder is moved to a forward position in the casing.

5. In a pencil, a casing having a longitudinal slot therein, a sleeve within the casing having a slot aligned with said first slot, a slotted tube arranged within said sleeve, a plate engaging an annular recess of said sleeve, means extending 10 through said plate and said sleeve engaging said slotted tube for securing the sleeve and the tube in the casing, a rotatable guide member having grooves, a plurality of lead holders longitudinally movable within the casing, an elongated spring 15 carried by each lead holder movable in the groove aligned with said slots, a handle carried by the spring and adapted to be moved in said slots, and said spring being adapted to engage the edge of

said slotted tube for maintaining the lead holder in a projected position.

6. In a pencil, a casing having a longitudinal slot therein, a sleeve fixed within the casing and having a slot aligned with said first slot, a slotted tube fixed within said sleeve having its slot aligned with the first mentioned slots, a rotatable guide member having a tubular portion provided with openings, a plurality of lead holders, an elongated spring carried by each lead holder, a thrust handle carried by each spring adapted to be moved into said openings, said slotted tube having a plurality of recesses in an end thereof, a spring urging said guide member towards the end of the slotted tube and the thrust handles in 15 operable relation with respect to said recesses.
